(57) **CLAIM**

The ornamental design for a vehicle lift gate, as shown and described.

DESCRIPTION

FIG. 1 is a front perspective view of a vehicle lift gate showing our new design;

FIG. 2 is a rear perspective view thereof;

FIG. 3 is a front elevational view thereof;

FIG. 4 is a rear elevational view thereof;

FIG. 5 is top plan view thereof;

FIG. 6 is a bottom plan view thereof;

FIG. 7 is a right side elevational view thereof; and,

FIG. 8 is a left side elevational view thereof.

It will be understood that the broken lines shown in the drawings illustrate portions of the vehicle lift gate that form no part of claimed design.
